(57) **CLAIM**

The ornamental design for an interceptor blade, as shown and described.

DESCRIPTION

FIG. 1 is a front, bottom, left side perspective view of a first embodiment of an interceptor blade;

FIG. 2 is a rear, top, right side perspective view of the embodiment of FIG. 1;

FIG. 3 is a front view of the embodiment of FIG. 1;

FIG. 4 is a rear view of the embodiment of FIG. 1;

FIG. 5 is a right side view of the embodiment of FIG. 1;

FIG. 6 is a left side view of the embodiment of FIG. 1;

FIG. 7 is a top view of the embodiment of FIG. 1, and

FIG. 8 is a bottom view of the embodiment of FIG. 1.

FIG. 9 is a front, bottom, left side perspective view of a second embodiment of an interceptor blade;

FIG. 10 is a rear, top, right side perspective view of the embodiment of FIG. 9;

FIG. 11 is a front view of the embodiment of FIG. 9;

FIG. 12 is a rear view of the embodiment of FIG. 9;

FIG. 13 is a right side view of the embodiment of FIG. 9;

FIG. 14 is a left side view of the embodiment of FIG. 9;

FIG. 15 is a top view of the embodiment of FIG. 9, and

FIG. 16 is a bottom view of the embodiment of FIG. 9.

FIG. 17 is a front, bottom, left side perspective view of a third embodiment of an interceptor blade;

FIG. 18 is a rear, top right side perspective view of the embodiment of FIG. 17;

FIG. 19 is a front view of the embodiment of FIG. 17;

FIG. 20 is a rear view of the embodiment of FIG. 17;

FIG. 21 is a right side view of the embodiment of FIG. 17;

FIG. 22 is a left side view of the embodiment of FIG. 17;

FIG. 23 is a top view of the embodiment of FIG. 17, and,

FIG. 24 is a bottom view of the embodiment of FIG. 17.

The broken line illustrate portions of the interceptor blade which form no part of the claimed design.
